HAND BRUSH OR THE LIKE

Joseph Vallis, 448 Spadina Road, Toronto,
Ontario, Canada

Filed Aug. 29, 1960, Ser. No. 61,915

Term of patent 14 years

(Cl. D9—2)

Fig. 1

Fig. 2.

Fig. 3.

Fig. 1 is a side elevational view of a hand brush or the like, showing my new design;

Fig. 2 is an end elevational view thereof; and

Fig. 3 is a top plan view thereof.

The dominant features of my design reside in the portions shown in full lines.

The side and end not shown are substantially like the side and end shown.

I claim:

The ornamental design for a hand brush or the like, as shown and described.
